BUILDING METHOD AND CONSTRUCTION

Joel Pomerene, Chicago, Ill., assignor to United States Gypsum Company, Chicago, Ill., a corporation of Illinois

Application April 18, 1935, Serial No. 16,958

11 Claims. (Cl. 20—4)

This invention relates to building constructions, and has reference more particularly to porous ceiling and wall constructions in which provision is made to prevent breathing through the porous 5 ceiling or wall into an air space behind the wall or above the ceiling, with a resultant soiling of the wall or ceiling.

Where there is an air space between a wall or ceiling construction and adjoining rooms or the 10 floor or roof above, there has always been trouble due to a deposit of dirt on the wall or ceiling due to an action which has been termed "breathing". Thus, in ceiling constructions this breathing action is due to the difference in temperature between the air in the space between the ceiling or 15 the roof above and the temperature of the air in the room below the ceiling. This difference in temperature causes the air in the space where the temperature is higher to expand, causing a difference in air pressure on the opposite sides of 20 the ceiling construction. This difference in temperature is, of course, compensated by air from the higher pressure side filtering through the porous ceiling construction until the pressure on the 25 two sides is equal. In passing through the ceiling construction, the dirt in the air is deposited on the surface, and this of course discolors the ceiling and is very objectionable. This action has commonly produced "lath marks" on ordinary 30 plaster ceilings which are more or less porous in nature.

Due to the necessarily porous nature of acoustical materials, this action has been particularly objectionable where acoustical treatment has 35 been used on walls and ceilings, and manufacturers and builders have been trying to find a way to overcome this breathing action. Various methods of sealing the upper or reverse surface of such acoustical materials to make the wall or 40 ceiling air-tight have been tried, but in most cases I have found that this is practically an impossibility, as there are always some places which are not completely sealed, from which it follows that the breathing is confined to these small 45 areas, and the deposit of dirt on the surface is thus very much accentuated.

An object of this invention, therefore, is to provide means in connection with a porous wall or ceiling to prevent the filtering of air through 50 said wall or ceiling by equalizing air pressures above and below said ceiling or on both sides of said wall. In its simplest embodiment, the present invention accomplishes this object by providing an enlarged opening, or a plurality of 55 openings, between the wall or ceiling and the next

adjoining space so that any air-pressure differential between the room and the space may cause a flow of air practically entirely through the openings rather than through the fine pores or interstices of the wall or ceiling itself. These openings should be large enough to prevent filtration of air through the porous wall or ceiling. The openings may be distributed at various points in the ceiling or wall, but for most purposes a fair sized opening, say, about one foot square, establishing free communication between the room and the adjoining space, will be sufficient. In many cases the space behind the wall or ceiling is a dead air space, but the invention is not limited to such dead air spaces. In most cases of preventing reverberation of noise in a room, it is the ceiling only that is lined with sound-absorbing tile or plaster, and hence, in its specific embodiment, the invention finds its greatest utility in connection with ceilings that are either naturally 20 porous or deliberately made porous to permit of entrapment of impinging sound waves.

Another object of the invention is to prevent the soiling of acoustical ceilings, also to improve building constructions and methods in other respects hereinafter specified and claimed. As a specific embodiment of the present invention, its use with an acoustically sound-absorbing ceiling will be described.

Reference is to be had to the accompanying 30 drawing forming a part of this specification, in which

Figure 1 is a perspective view showing one form of the improved building construction;

Fig. 2 is a sectional elevation through said 35 building structure;

Fig. 3 is a sectional elevation showing a modified form of building construction;

Fig. 4 is a sectional elevation showing a further modified form of building construction; 40

Fig. 5 is a perspective view of a ventilator used in the construction shown in Fig. 4;

Fig. 6 is a sectional elevation through a further modified form of the invention;

Fig. 7 is a perspective view of a still further 45 modified form of ventilator; and

Fig. 8 is a further modification of the invention, employing a molding spaced from the wall and openings in the ceiling adjacent the wall.

In constructing a building having side walls 50 and ceiling rafters or framework 11, it is common to support a floor 12 on top of said rafters and support a ceiling below said rafters. The ceiling may comprise plaster or other building boards 13 which are secured by nails or the like 55

to furring strips 14 which in turn are secured to the bottoms of rafters 11. Acoustical tiles 15 of a porous, sound absorbing material are secured by an adhesive or other suitable material 5 to the bottom faces of the boards 13. The ceiling forms an air space 16 above the boards 13 and about the rafters 11. In order to equalize the pressure of heated air below the ceiling and cooler air within the air space 16, I provide an 10 opening 17 in the boards 13 and tiles 15 so that air may freely flow into the air space 16 without being forced through tiles 15 and boards 13, thus preventing the tiles 15 from becoming soiled due to the effect of dirt and dust filtered from the 15 air that would otherwise pass through the tile. A foraminous closure or grille 18 is secured across the opening 17, being inset between the tiles 15. A frame 19, preferably of angle strips, is secured around the periphery of the grille 18 so as to 20 present a finished appearance.

The modified construction shown in Fig. 3 differs from that shown in Fig. 2 in that a grille is secured, as by nailing, to the outer face of tiles 15. The form shown in Fig. 2 is somewhat preferable to that shown in Fig. 3 in that dirt-depositing air currents are kept away from the outer face of tiles 15 by the grille-frame 19. My invention is also applicable to ordinary metal or 25 wood lath and plaster walls and ceilings which are porous in nature and quickly show up lath marks due to air filtration through the wall or ceiling.

In the form of invention shown in Figs. 4 and 35 5, a foraminous metal pan 21 is provided with upturned end flanges 22 and upturned side flanges 23, said flanges fitting snugly within the ventilating opening 24. The side flanges 23 are wider than the flanges 22 so as to provide a ventilating space below the rafters 11 (Fig. 4). Any 40 desired shape of slots or holes 25 may be provided in the pan face 21 to permit the passage of air therethrough.

In the construction shown in Fig. 6, I employ 45 steel beams 26 for supporting the floor 27, and cross runners 28 are secured below the beams 26. A sheet of expanded metal lath 29 is secured to the runners 28 by wires 30, and common plaster or acoustical plaster 31 is applied to the lower 50 face of said metal lath, a ventilating opening 32 being provided in said plaster to permit air pressure to equalize in the dead air space about the beams 26. A grille 33 is applied over the opening 32, being secured by clips 34 to the unplastered portion of the metal lath 29.

In Fig. 7 I have illustrated a special form of 55 ventilating grille which may consist of an acoustical tile 35 which has its exposed face painted or otherwise treated to permit the exposed face 36 of said tile to be washed or otherwise cleaned 60 when it becomes soiled. Holes or openings 37 are provided in the tile 35 to permit the passage of air into the air space as previously described. It should be understood that all of the grilles hereinabove described are preferably painted or 65 otherwise treated to permit cleaning when they become soiled.

Still a further modification of the invention is 70 shown in Fig. 8. This construction substantially completely conceals the means by which free communication between the room and the adjoining space is obtained. The ceiling 13 is so constructed as to leave, at intervals, a space 40 between the wall 10 and the ceiling. A suitable molding 41 is nailed or otherwise fastened to the 75 wall 10 by means of nails or screws 42, interpos-

ing suitable spacing-blocks 43 so as to leave open spaces 44 between the molding and the wall, communicating with the openings or spaces 40 between the ceiling and wall. This will therefore permit air to flow from the room and the space 5 behind or above the ceiling as shown by arrow 45.

In order to conceal the existence of the space between the wall and molding 41 from the eyes of occupants of the room, a second molding 46 may be attached to the wall 10 a short distance 10 below the first, spaced, molding 41, leaving a space 47 for passage of air currents as indicated by the arrow 48. In this way the building up of a plenum of pressure and filtration of air through the porous ceiling will be prevented.

I would state in conclusion that while the illustrated examples constitute practical embodiments of my invention, I do not wish to limit myself precisely to these details, since manifestly they may be considerably varied without departing 20 from the spirit of the invention as defined in the appended claims. Thus a plurality of grilles may be employed, either of the same size or smaller than the tile. Alternatively, a long narrow slot covered with a suitably perforated 25 strip may be employed. This may form part of a panel-like decorative effect. Inasmuch as the main object is to insure absence of flow of air through the tile or plaster itself, any means for establishing preferential air-flow through the 30 wall or ceiling at predetermined points or places is to be considered as within the scope of the present invention.

Having thus described my invention, I claim 35 as new and desire to secure by Letters Patent:

1. In a building construction, supporting building framework, a floor supported on top of said framework, a porous ceiling supported below said framework and forming an air space between said floor and ceiling, said ceiling being provided 40 with a ventilating opening to establish free communication between the room and the air space.

2. In a building construction, a substantially horizontal building framework, a floor and a porous ceiling supported by said framework and 45 forming an air space about said framework, said ceiling being provided with a ventilating opening, and a foraminous grille positioned in said opening.

3. In a building construction, a substantially 50 horizontal building framework, a floor supported on top of said framework, and a ceiling supported below said framework and forming an air space between said floor and ceiling, said ceiling being composed in part of surfacing of porous, sound 55 absorbing material, said ceiling being provided with a ventilating opening into said air space to establish free communication between the room and the air space.

4. A construction for preventing breathing and 60 soiling of a porous ceiling by the passage of air through said ceiling into an air space above said ceiling, which comprises a ventilating opening in said ceiling so that air pressure below said ceiling is equalized with the air pressure in said air space, 65 thus retarding the passage of air through the pores of said ceiling.

5. A construction for preventing accumulation 70 of dirt and development of lath marks on a porous ceiling of a room which comprises means for the escape of air from said room at some point in said ceiling in amounts sufficient to prevent the accumulation of a layer of heated air immediately below the ceiling.

6. The method of correcting the acoustic prop- 75

erties of a room which comprises lining at least the ceiling of said room with a porous sound-absorbing material and providing at at least one point on said ceiling grilled ventilating means to prevent the accumulation of a plenum of pressure in said room.

5 7. In a building construction, the combination of a room having walls and a ceiling, porous sound-absorbing material on said ceiling, the latter being provided with at least one ventilating opening communicating with an adjacent space, and a grille across said opening.

10 8. In a building construction comprising a room having walls, floor and a ceiling, the ceiling being at least in part composed of porous air-permeable material, the improvement which comprises means of escape of air from said room between said ceiling and wall, and a molding concealing said means.

15 20 9. In a building construction, the combination of a room having walls and a ceiling, porous sound-absorbing material on said ceiling, the

latter being provided with at least one ventilating opening communicating with an adjacent space, and a molding spaced sufficiently below said opening not to obturate the same but sufficiently close thereto substantially to conceal it 5 from the view of an occupant of said room.

10 10. In a building construction, a substantially horizontal framework, a floor and a porous sound-absorbing ceiling supported by said framework and forming an air space about said framework, 10 said porous ceiling being also provided with openings to permit relatively free passage of air between the space and the room below the ceiling.

15 11. In a building construction, the improvement which comprises a room bounded by a floor, walls and a ceiling, there being a space above the ceiling, a porous sound-absorbing covering on the ceiling, and openings therein to establish free communication between the room and the air space.
